UNITED STATES PATENT OFFICE.

MYRON HOLLEY PIPER, OF WALPOLE, MASSACHUSETTS, ASSIGNOR, BY MESNE ASSIGNMENTS, TO HIMSELF AND CHARLES S. BIRD, OF SAME PLACE.

FIRE-EXTINQUISHING GRENADE.

SPECIFICATION forming part of Letters Patent No. 324,414, dated August 18, 1885.

Application filed June 1, 1885. (No model.)

To all whom it may concern:

Be it known that I, MYRON HOLLEY PIPER, of Walpole, in the county of Norfolk, of the Commonwealth of Massachusetts, have invented a new and useful Improvement in Fire-Extinguishing Grenades; and I do hereby declare the same to be described in the following specification and represented in the accompanying drawings, of which—

10 Figure 1 is a front view, and Fig. 2 a side elevation, of a fire-extinguishing grenade provided with my invention, the nature of which is defined in the claim hereinafter presented.

The grenade shown at A is a glass bottle charged with a composition or with materials or matters, such as, on breakage of the bottle, will generate carbonic-acid gas, or some other gas destructive of flame or fire. In the drawings, such grenade is represented as supported 15 by and arranged within a wire frame or bail, B, having applied to it a mechanism for breaking the grenade in case of a fire taking place in proximity with it, and raising the temperature of the surrounding air sufficiently to 20 melt the fusible metal by which the mechanism is held from acting on the grenade. The said mechanism consists of a hammer, C, whose head *a* tapers like that of an ax, and is applied to a wire, *b*, extending downward

25 toward and coiled around a cylindrical block, *c*, within the bail fixed thereto, the said wire at its lower end being hooked upon the bail. Near the hammer-head there is within and 30 fixed to the bail a cross-piece, *d*, of metal, to

35 which, by means of fusible metal *m*, an arm, *e*, projecting from the hammer, is soldered, the said fusible metal being melttable at a temperature of about 140° Fahrenheit. The hammer is so arranged that, on melting the fusible

metal, the spring shall throw the hammer 40 down to cause its head to strike against the grenade with force sufficient to break it.

The device shown for holding the hammer and grenade is of a character to enable it to be hung or suspended on a nail or hook; but 45 it may be otherwise constructed for the purpose of supporting the hammer and grenade.

I am aware that it is not new to have a fire-extinguishing grenade provided with a hammer held to the grenade-frame by a fusible 50 fastening, and thrown against the receptacle by a spring when the fastening melts. As far as I am aware, in such prior devices the receptacle itself moves when the fastening melts, or else is unprotected by a frame, and liable to 55 accidental breakage.

In my device the bail B is a rigid frame, which holds the grenade A in one position, from which it is not moved; in fact, the grenade is a portion of the stationary structure, 60 the hammer C alone moving, and the bail B encompassing the grenade protects it.

Having described my invention, what I claim is—

The grenade A, in combination with the 65 bail B, the latter encompassing and supporting the former, said grenade being a portion of the stationary structure, with the bail, and the hammer C, consisting of a spring, *b*, and head *a*, and the fusible fastening holding the 70 hammer to the bail, whereby the grenade is protected from accidental breakage, and the hammer is the only movable part, as set forth.

MYRON HOLLEY PIPER.

ERNEST B. PRATT.

Correction in Letters Patent No. 324,414.

It is hereby certified that in Letters Patent No. 324,414, granted August 18, 1885, upon the application of Myron Holley Piper, of Walpole, Massachusetts, for an improvement in "Fire-Extinguishing Grenades," an error appears in the printed specification requiring correction as follows: In line 68, the comua between "structure" and "with" should be stricken out; and the said Letters Patent should be read with this correction therein that the same may conform to the record of the case in the Patent Office.

Signed, countersigned, and sealed this 3d day of November, A. D. 1885.

[SEAL.]

H. L. MULDROW,
Acting Secretary of the Interior.

Countersigned:

M. V. MONTGOMERY,
Commissioner of Patents.
